UNITED STATES PATENT OFFICE.

ANDREW J. BEARD, OF EASTLAKE, ALABAMA.

AUTOMATIC CAR-COUPING.

SPECIFICATION forming part of Letters Patent No. 761,056, dated May 31, 1904.

Application filed September 2, 1903. Serial No. 171,623. (No model.)

To all whom it may concern:

Be it known that I, ANDREW J. BEARD, a citizen of the United States, residing at Eastlake, in the county of Jefferson and State of Alabama, have invented certain new and useful Improvements in Automatic Car-Couplers, of which the following is a specification.

My invention relates to improvements in automatic car-couplers of the twin-jaw type, comprising a draw-head and a knuckle pivoted thereto, which swings in a horizontal plane and engages the knuckle of an opposing head and is locked in engagement therewith to couple the cars.

It is the object of my invention to provide a coupler with a simple and durable locking device which will act positively without dependence upon a gravity movement to lock the knuckle in a closed position and also to throw it to its open position preparatory to effecting a coupling.

According to my invention I recess the draw-head to provide a chamber within which a curved locking-piece moves freely and bodily without fixed pivot, and I adapt this locking-piece to be engaged and moved positively by the tail-wing to a position where it will block the latter's outward movement and to engage and move the tail-wing to its open position as it is lifted to permit the knuckles to uncouple.

My invention comprises the construction and arrangement of parts hereinafter described, and more particularly pointed out in the claims, reference being had to the accompanying drawings, in which --

Figure 1 is a top plan view of my improved coupler. Fig. 2 is a vertical longitudinal section through the line $\pi\pi$ of Fig. 3. Fig. 3 is a transverse horizontal longitudinal section showing the knuckle locked by the curved piece in its closed position. Fig. 4 is a similar view showing the manner in which the locking device when in its open position is engaged by the tail-wing, while Fig. 5 illustrates the operation of the wedged end of the tail-wing acting to raise the locking-piece from its closed position to effect a coupling. Fig. 6 is a transverse section through line 67 of Fig. 3, showing the locking-piece in its

closed position, and Fig. 7 is a similar view showing it in its open position. Figs. 8 and 9 are enlarged detail views of the curved locking-piece. Fig. 10 is an enlarged view of the wedged end of the tail-wing.

Similar reference-numerals refer to the same parts throughout.

The draw-head 1, having the jaws 2 and 3 of ordinary construction, is provided with a recess in its inner face, into which the tail-wing 4 of a knuckle 5 swings when moved to a locked position. This knuckle 5 is pivotally mounted in jaw 2 by a pin 6, at which point the metal is thickened and strengthened by a bracing web or ridge 7, which leads rearward to the forward wall of the curved chamber 8, provided for the locking device. The rear wall of said chamber forms the buffer-shoulder for the head, the latter being pivotally secured by pin 9 to the end of the draw-bar 10 to provide for a limited lateral swing or play, which will reduce its strain on rounding curves and will also enable it to couple on curves. The end of the draw-bar is cut away and reduced to form two circular lugs 11, through whose centers an opening 12 is provided for a pin by means of which similarly-shaped perforated lugs 13, formed on the head at its back, are pivotally secured to the draw-bar. There are three of these lugs 13, the outer of which are seated flush in the curved cut-away portions above and below the lugs 11 of the draw-bar, and the inner lug 13 passes between the said lugs 11 and bears against the curved inner wall of the recess. It will be noted that this manner of forming and pivoting the head of the draw-bar causes the parts to have full contact in all positions except at the points 14, provided to permit sufficient lateral swing for the head around its pivot. Hence the power to withstand a great pressure strain is increased by transferring the pressure from the pin to the curved walls and abutting flanges or lugs, and at the same time the shearing strain on the pin is entirely relieved.

The chamber 8, which leads vertically upward from the rear portion of the recess in the draw-head, has one of its side walls con-

structed to form a locking-shoulder 15, while its top portion is curved for the purposes hereinafter described. Within this chamber is a freely-movable locking device 16, which I call the "curved piece" by reason of the outer contour of its tailpiece 17. This tailpiece, which is preferably thinner and lighter than the locking head or block 18, is rigidly connected thereto by a pin 19 passing through openings in the end of the tailpiece and in the lugs 20 in said block. I may make the curved piece integral; but its size, and therefore its strength, would be reduced to enable it to be slipped through the front recess in the draw-head, for the unnecessary enlargement of the recess-opening to enable a curved piece of this size to be inserted would weaken the head.

When a two-part locking device is used, the piece 17 is first inserted into the chamber and then the block 18, and when they have been moved into proper position and slightly lifted the pin 19, which connects the two parts, will be inserted through an opening 21 in the rear wall of the chamber, which may be plugged to prevent the entrance of moisture or sand. The block 18 being of almost equal width with the chamber, it will be impossible for the pin to work loose after it has once been inserted in the manner described. Before, however, the block has been inserted an operating-rod 22, which has its inner end bent to the side at right angles to engage an opening 23 in the side of the tailpiece 17, should be inserted through an opening 24 in the side wall of the chamber and have its inner end moved opposite to the recess-opening in the draw-head. When in this position, its bent end should be inserted into the opening 23 in the tailpiece, after which the latter may be lifted or drawn up into the chamber 8 by said rod and placed in position to engage the upper end of the block 18 when the latter is inserted into the head. The chamber 8 is too narrow to permit the angled end of the rod to disengage itself from the locking device.

The rod 22 is bent upwardly near its inner end, so that it will have a substantially straight pull on the curved piece throughout its movements, and an eye 25 in the outer end of said rod is for a connection to an operating rod or chain leading to any convenient point on the car.

I round off or bevel the lower front side of the block 18 and also the lower corner disposed toward the front opening to the recess in the head.

The tail-wing 4, which curves forward from the knuckle to increase the latter's draft strength, is provided with an angled end portion 27, curved over the top and having front and back parallel sides or faces. From the outer end a wedge-shaped flange 28 forms a

rearward continuation of the curved top of the tail-wing and leads to a point in the same plane with the lower or bottom-side of the tail-wing. The inward swing of end 27 on the knuckle pivot-pin 6 is stopped by its engaging within a similarly-wedge-shaped recess 29 in the rear wall of the chamber 8.

The tailpiece 17 is bent sidewise near its rear end, so that it will not engage the wedge 28 of the tail-wing, but will always strike and be struck by the rear flat side of the extension 27, as will be best seen in Figs. 2 and 4.

Having thus described the construction and arrangement of the several parts composing my coupler, I will now explain the manner of its operation.

Assuming the several parts of the locking device to have been assembled within the chamber 8 and the curved piece in its open position, as seen in Fig. 7, if now the knuckle be in the position shown in Fig. 1 and an incoming head engage it in the act of coupling it will be swung within the recess and the rear wall of 27 will strike the end of tailpiece 17, Fig. 4. This will force the rounded side of the said piece against the curved walls of the chamber 8 with the result that the curved piece will move bodily in the direction of a curve, and the block 18 will be forced downwardly between the front wall of 27 and shoulder 15 of the head, securely locking the knuckle in its closed position, Figs. 3 and 6. When it is desired to uncouple, the rod 22 is drawn outwardly, and as it raises the curved piece the latter will move bodily until the block is above the end 27 and, acting with the side wall of the chamber 8 as a fulcrum, will cause the tailpiece to engage 27, Fig. 4, and force the tail-wing outwardly to open the knuckle. If now the curved piece shall have fallen or been moved to its closed position after the knuckle has been opened as the tail-wing swings inwardly in coupling, the wedge 28 will slip under the lower cut-away corner of the block, Fig. 5, and since the curved piece is freely movable within the chamber 8 without fixed pivot or any rigid connection it will readily be lifted upwardly and will ride over the curved top of the end 27 and drop behind the same to lock the knuckle. The engagement of end 27 within recess 29 prevents the possibility of breaking the tailpiece 17 of the locking device by jamming it against the side of the head; but it engages the tail-wing and throws it sufficiently to force the curved piece by a positive action into a position when its block will lock the tail-wing. I thus avoid any gravity or other uncertain action for my locking device, which is positive in its every movement and is yet freely movable within its chamber. It has no fixed pivot, which is a point of great weakness in similar couplers, and will move to lock the knuckle whatever position it may be in or to

open the same in the simplest and most durable manner. It cannot be broken, for when in a locking position the recess 29 on one side and the shoulder 15 on the other relieve it entirely of draft strain or pressure in either direction, and when in an open position it will jump freely away from any blow of the tail-wing.

The details of construction may be varied 10 without departing from the gist of my invention, which consists principally in so forming the locking device that it acts positively but without fixed pivot and can be automatically operated by the tail-wing when it has fallen 15 to a closed position behind it. Thus the locking-chamber may be formed as a horizontal continuation of the recess in the head, which form would be more applicable to solid-head coupler.

20 Having thus described my invention, what I claim as new, and desire to secure by Letters Patent, is—

1. A coupler comprising a recessed draw-head, a swinging knuckle having a tail-wing, 25 a curved knuckle locking and opening device movable freely and without fixed pivot within said head and disposed in the path of said tail-wing by which it is engaged and shifted to intercept said tail-wing's outward movement, and means to move said device to release the knuckle.

2. A coupler comprising a recessed draw-head, a pivoted knuckle having a tail-wing which swings into said recess, a curved locking device movable without fixed pivot within a portion of said recess and engaging said tail-wing to be moved thereby to a position astride it to block its outward movement.

3. A coupler comprising a recessed draw-head, a pivoted knuckle having a tail-wing, a locking device movable without fixed pivot within said draw-head and comprising a head and a guide body portion which engages said tail-wing to force said head into a position between it and the draw-head to lock the knuckle.

4. A coupler comprising a recessed draw-head a locking-chamber leading therefrom, a shifting locking device in said chamber having a head and a curved tailpiece, a swinging knuckle having a tail-wing which engages said tailpiece and forces its curved side against a wall of said chamber to positively shift said device until its head blocks the outward swing of said tail-wing, and means to move said device to release the knuckle.

5. A coupler comprising a recessed draw-head, a locking-chamber therein, a shifting locking device in said chamber having a head and a curved tailpiece, a swinging knuckle having a tail-wing which engages said tailpiece and forces its curved side against a wall of said chamber to positively shift said device

until its head blocks the outward swing of said tail-wing, and an operating-rod to move said head out of the path of the tail-wing and force its tailpiece by a reverse shifting action to engage and throw said tail-wing outwardly to open the knuckle.

6. A coupler comprising a recessed draw-head, a loose locking device therein having a locking end and a curved guide portion which straddles the tail-wing of a pivoted knuckle when in its locked position, and a bent rod pivotally connected to said device which draws the curved portion thereof against an inner wall of the head causing it to shift bodily and unlock and open the knuckle with the same movement.

7. A coupler comprising a recessed draw-head, a vertically-disposed chamber having a curved upper wall, a pivoted knuckle whose tail-wing swings into said chamber in the rear wall of which a shoulder is provided to form a stop for the said tail-wing, and a curved locking device freely movable in said chamber.

8. A coupler comprising a recessed draw-head, a locking device freely movable in said head and whose locking end has a lower beveled edge, a swinging knuckle having a tail-wing with a rearwardly-disposed wedge-shaped projection near the end thereof and adapted to engage said beveled edge and lift it to couple when the locking device has fallen to a closed position behind said tail-wing.

9. In a coupler, a pivoted knuckle having a tail-wing whose outer end is formed with flat front and back sides, a curved top portion, and a tapering flange leading from said top portion rearwardly to a point in the plane of the bottom of said tail-wing.

10. A coupler comprising a recessed draw-head, a pivoted knuckle having a tail-wing, a locking device having a guide portion with a curved bearing-surface which shifts the device bodily into and out of its locking position when forced against an inner wall of said draw-head, said device being moved by said tail-wing to a locking position.

11. In a coupler, the draw-head having a knuckle pivoted in one jaw and being recessed to permit the tail-wing to swing thereto and be engaged by suitable locking means and a vertically-disposed locking-chamber leading up from said recess and having one side forming a locking-shoulder, and a curved top portion the rear wall of which forms a buffer-shoulder for said head.

12. In a coupler having a recessed draw-head and a swinging knuckle, a substantially β -shaped locking device which is engaged by said knuckle and moved in an arcuate direction without fixed pivot to lock or release the said knuckle, and means to move said device, to release said knuckle.

13. In a coupler having a recessed draw-head and a swinging knuckle, a locking device provided with a guide portion and adapted to engage said knuckle and be moved bodily in
5 an arcuate direction when said guide portion is forced against a wall of the coupler-head by the knuckle as it swings inwardly in coupling.

In testimony whereof I affix my signature in presence of two witnesses.
